(57) **CLAIM**

The ornamental design for a notebook computer, as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof in an opened position;

FIG. 9 is an enlarged view of the circled portion so indicated in FIG. 1 thereof;

FIG. 10 is an enlarged view of the right circled portion so indicated in FIG. 2 thereof;

FIG. 11 is an enlarged view of the left circled portion so indicated in FIG. 2 thereof;

FIG. 12 is an enlarged view of the circled portion so indicated in FIG. 4 thereof;

FIG. 13 is an enlarged view of the circled portion so indicated in FIG. 5 thereof;

FIG. 14 is an enlarged view of the right circled portion so indicated in FIG. 6 thereof;

FIG. 15 is an enlarged view of the left circled portion so indicated in FIG. 6 thereof;

FIG. 16 is an enlarged view of the right circled portion so indicated in FIG. 7 thereof;

FIG. 17 is an enlarged view of the left circled portion so indicated in FIG. 7 thereof; and,

FIG. 18 is an enlarged view of the circled portion so indicated in FIG. 1 thereof.

The dot-dashed broken lines represent a boundary of the claimed design and form no part of the claimed design. The dashed broken line showing of portions of the notebook computer is for the purpose of illustrating unclaimed portions of the notebook computer and forms no part of the claimed design.

1 Claim, 13 Drawing Sheets
